METHOD OF COKING HYDROCARBON LIQUIDS

Harold V. Atwell, White Plains, N. Y., assignor to
 Gasoline Products Company, Inc., Newark,
 N. J., a corporation of Delaware

Application March 29, 1933, Serial No. 663,290

1 Claim. (Cl. 202—36)

My invention relates to coking liquid or liquefiable hydrocarbon material, such, for example, as residuums or tars derived from the distillation or cracking of petroleum oil, and other hydrocarbon liquids of petroleum and non-petroleum origin, such as crude or partially distilled petroleum, coal tar, coal tar pitch and analogous hydrocarbon materials, and an object of my invention is to provide a method whereby material of the character recited may be coked in a suitable vessel, and whereby the resultant coke may be removed from the vessel in which it is produced more readily than has been true of the method and apparatus applied in the prior art.

My invention has for further objects such additional operative advantages and improvements as may hereinafter be found to obtain.

In coking liquid or liquefiable hydrocarbon material in the past it has frequently been found to be difficult to remove the coke from the vessel in which the coking takes place. The material to be coked usually passes through a state of high fluidity just prior to the time at which solidification or coking takes place, and tends to adhere strongly to or to penetrate into the walls of the coking vessel, depending upon the nature of the material of which the vessel is constructed. While removal of petroleum coke or pitch coke from a coking chamber or vessel may be facilitated by carrying out the coking operation at a very high temperature, for example, 1600° F. or higher and subsequently "calcining" the coke at that temperature for a period usually amounting to several hours, in many instances this is either undesirable or impracticable. Such procedure requires considerable time and additional apparatus of an expensive character, such as by-product coke-ovens or the like.

Removal of coke has been a problem in the oil-cracking art, in those instances at least in which a definite coking operation is conducted in conjunction with or rather as a part of a cracking operation, due to the fact that the temperature of the coking operation is ordinarily limited to a temperature of, for example, 1100° F., or considerably less, and is accomplished in metal drums or vessels, from which coke can only be removed by coke boring apparatus or the like at the expense of disintegrating or pulverizing the coke. This results in a material reduction of the ultimate value of the coke, due to the small size and low strength of the final coke product.

According to my invention, these and other difficulties encountered by the prior art may be overcome in a simple and efficacious manner.

My invention contemplates providing interior surfaces of a vessel in which it is desired to effect the coking of a hydrocarbon liquid with a coating of substantial thickness of a material which is more or less friable at the temperature at which the coking takes place or which may be made relatively friable with respect to the coked mass after the coking operation has been completed, and having a surface which is substantially impervious with respect to the hydrocarbon liquid being coked.

The coating thus provided effectively separates the coked mass from the interior walls of the coking vessel, thus preventing the coke or the material being coked from adhering to or penetrating the walls of the coking vessel. The impervious surface of the coating or lining prevents the material being coked from penetrating into or through the coating or lining, at least to any material extent, so that at the completion of the coking operation there remains between the coke and the inner wall of the coking vessel a layer of material which as will be explained more fully hereinbelow is either relatively friable with respect to the coke or may be easily made so. When a force is applied to the mass of coke in a suitable manner, a disintegration or breaking down of the relatively friable lining takes place and the mass of coke comes out of the coking vessel or chamber easily and without serious destruction.

As mentioned hereinabove, my invention contemplates a lining or coating of substantial thickness, by which is meant a thickness of sufficient magnitude to permit a shearing or disintegrating of the coating material for the purpose of effecting removal of coke. Thus the thickness of the coating may be, for example, $\frac{1}{4}$ inch, or under occasional circumstances might even be somewhat less, although ordinarily coatings of $\frac{1}{2}$ inch thickness or more are preferred.

My coating is thus sharply distinguished from mere protective coating or glazes applied to the walls of vessels intended for the treatment of hydrocarbon liquids and other materials, in which the purpose is merely to protect the material of the vessel itself from contacting with the material being treated, but in which a thickness of material and a character of material of such nature as to permit removal of solidified material within the vessel by a shearing or disintegration of the coating itself are neither contemplated nor possible.

As stated hereinabove, the coating which I apply to the inner surface of a vessel in which

hydrocarbon liquid is about to be coked is of a more or less friable character, however, the coating is of a sufficiently cementitious character to be applied in a layer of substantial thickness and 5 to resist destruction or crushing thereof to a material extent by the pressure of the material to be coked. Moreover, while it is preferred to provide a lining material which tends to partially disintegrate or at least become weaker or 10 more friable at the temperature at which coking is effected, I may provide material which retains a relatively high strength throughout the coking operation, but may subsequently be weakened or disintegrated in a simple manner, as for example 15 by treating it with water or other liquid having solvent or disintegrating properties with respect to the same, without material injury to or destruction of the coked mass.

My invention also contemplates the provision 20 of an apparatus for coking hydrocarbon liquid which comprises a vessel, preferably more or less elongated in configuration, having a lining of the character recited hereinabove and having also a discharge opening for removing coke therefrom 25 the size of which is sufficient to permit the removal of the coke from the vessel in a single slug or mass, together with suitable means for exerting a discharging force upon the coke for the purpose of shearing or disintegrating the 30 lining material within the vessel and thus expelling the coke from the vessel without materially destroying or pulverizing the coke itself.

The lining or coating applied to the interior surface of the vessel preferably consists of loosely 35 bonded granular or arenaceous material of sufficiently cementitious and refractory character to be applied in a layer of substantial thickness and to resist the crushing force exerted by the material being coked while sufficiently friable after 40 the coking has been completed to make possible its disintegration for the purpose of removing the coke from the vessel, and having a substantial impervious surface as aforesaid.

Thus, I may employ a mixture of sand, clay 45 and a suitable bonding agent such as water glass or sodium silicate. For example, I may employ a mixture comprising substantially equal parts of sand and clay made into a mortar or paste of suitable consistency by means of a solution of 50 sodium silicate in water.

When the material employed to form the coating does not tend to form its own impervious surface, or when it is desired to decrease whatever perviousness the surface of the lining may have, 55 the latter may be glazed in any known manner or may be rendered less pervious by applying thereto a thin layer of impervious material, for example, a metallic pigment. Thus, I may spray the lining or coating after it has been formed 60 with a suspension of flaked aluminum or bronzing powder in a suitable vehicle.

As an alternative or supplementary mode of procedure I may employ a lining or coating consisting in part of a material, preferably more or 65 less granular character and capable of being dissolved or disintegrated by a suitable agent after the coking operation has been completed. Thus I may add a soluble salt, such as sodium chloride, or any other soluble material of sufficiently 70 refractory character to the mix from which the lining or coating is made, thus providing a coating comprising a mixture of soluble and insoluble particles. At the time the coke is cooled, which is done with water in the usual manner, 75 the solvent action of the water upon the soluble

constituents of the liner greatly facilitates the breaking down or disintegration of the lining or coating material and the removal of coke from the vessel.

In order that my invention may be fully set forth and understood, I have illustrated in the drawing accompanying and forming a part of this specification various preferred forms in which my invention may be practiced and embodied. In this drawing, 5

Figure 1 is a more or less diagrammatic elevational view of apparatus for effecting the coking of a hydrocarbon liquid in accordance with my present invention;

Figure 2 is an enlarged vertical sectional view 15 showing the relation of the wall of the coking chamber, the liner therefor and the material being coked; and

Figure 3 is a similar view, illustrating a different modification of my invention. 20

Similar reference numerals designate similar parts in each of the views of the drawing.

As illustrated in Figure 1, the vessel 1 in which the coking takes place is preferably more or less elongated and cylindrical in configuration and 25 is provided with openings at either end thereof, which are provided in turn with closures 2 and 3, respectively, and which openings are sufficiently large to permit the removal of the coked mass from within the vessel in a single mass or slug. 30

Prior to introducing material to be coked into vessel 1, I provide the interior surfaces of the vessel 1, or such portions thereof as may be expected to come into contact with material being coked, with a lining or coating 4 which, in 35 the preferred instance diagrammatically illustrated in Figure 2, comprises a mixture of substantially equal parts of sand and clay with a solution of sodium silicate and which coating material is applied until a layer of this mortar or 40 cement of a thickness of $\frac{1}{4}$ inch or more has been built up on the wall of the vessel 1.

After the lining or coating 4 has been applied it may if desired be dried in any suitable manner, as for example, by passing hot gases through 45 the vessel 1, although in most instances predrying will be unnecessary, it being satisfactory to effect the drying of the lining 4 during the progress of the coking process by the heat of the material being coked.

After the lining has been applied, the surface thereof may if desired be coated with a layer 5 of impervious material, such, for example, as a thin layer of metallic paint, as illustrated in Figure 3. Figure 2 is intended to show, however, in 55 a more or less diagrammatic way, the tendency of sodium silicate present in the material forming the layer 4 to make the exposed surface of the layer 4 substantially impervious by forming a sodium silicate glaze over or through the same, 60 while leaving the remaining portion of the lining or coating 4 in a less glazed or more friable condition.

When the coating or lining has been prepared, hydrocarbon liquid to be coked, is introduced into 65 the vessel 1 and is maintained within the vessel 1 within a sufficient temperature to effect coking thereof. In the instance illustrated in Figure 1 a hydrocarbon liquid such, for example, as a reduced crude or a gas oil, is drawn from a suitable 70 source (not shown) and is delivered by a pump 10 through a conduit 11 into heating coils 12 located within a suitable furnace 13, the heating being regulated with respect to the character of the material being heated to bring the liquid to 75

a temperature sufficient to promote coking of the liquid in the vessel 1, without, however, causing an undesirable deposition of coke or carbon within in the heating coils 12.

5 The heated liquid or vapor, which may, for example, be at a temperature of 850 to 1050° F., then passes through a transfer line 14 having valved branches 15 and 16 into the vessel 1, the admission being either to the top or to the bottom of the same or divided between the top and bottom 10 of the vessel 1. In the vessel 1, separation of vapors and liquid occurs and the unvaporized liquid is coked by the contained heat of the material entering the vessel 1. The vapors pass off through 15 a vapor outlet pipe 20, the coke building up within in the vessel 1 but separated from the walls of the latter by means of the lining or coating 4.

When the coking operation has been completed, that is to say, when a sufficient amount 20 of coke has accumulated within the vessel 1, the introduction of hydrocarbon liquid is discontinued and the closures 2 and 3 are removed. The coked mass may then be expelled from the vessel 1 in any desired manner, for example by means of a 25 pusher ram 21 of sufficient size with respect to the interior of the vessel 1 to cause the coked mass to be expelled from the bottom of the vessel 1 in a single mass or slug, this removal of the coke being greatly facilitated by the disintegration 30 of the more or less friable lining or coating 4.

The coke may be cooled either before or after

removing it from the vessel 1 in any suitable manner, as for example, by treating it with water, the latter being especially desirable where, as has been indicated hereinabove, the material comprising the lining 4 contains soluble constituents which may be dissolved by the water, thus assisting in the breaking down or disintegration of the lining 4 prior to the removal of coke from the vessel 1.

It will be obvious to those skilled in the art 10 that, while I have described my invention hereinabove with respect to one or more specific illustrative examples, my invention is not limited to the details of such exemplification but may variously be embodied and practiced within the scope 15 of the claim hereinafter made.

I claim:

In the process of coking hydrocarbon oil within in a metal vessel, the steps which comprise lining the interior of the vessel with a cementitious layer 20 of substantial thickness, sealing the entire exposed surface of said lining by applying a thin metallic coating thereto, thereby preventing contact of oil to be coked with the inner cementitious layer, supplying oil to the vessel and maintaining 25 it at a coking temperature until coked, thereby rendering said cementitious layer frangible, and then discharging the coke produced together with the linings.

HAROLD V. ATWELL. 30
